UNITED STATES PATENT OFFICE

100,018

DESIGN FOR A RAILWAY CROSSING SIGNAL

Frank W. Griswold, Minneapolis, Minn.

Application December 30, 1935, Serial No. 60,345

Term of patent 14 years

To all whom it may concern:

Be it known that I, Frank W. Griswold, a citizen of the United States, residing at Minneapolis, in the county of Hennepin and State of Minnesota, have invented a new, original, and ornamental Design for a Railway Crossing Signal, of which the following is a specification, reference being had to the accompanying drawing, forming part thereof.

Fig. 1 is a view in front elevation of the railway crossing signal showing my new design; and
Fig. 2 is a view in side elevation thereof.

I claim:—

The ornamental design for a railway crossing signal, as shown.

FRANK W. GRISWOLD.
